Patented July 29, 1919.

FIG. 1.

五〇·三

ED. 3.

五九·4

Charles T. Link, Inventor
Howard R. Denison, Attorney

UNITED STATES PATENT OFFICE.

CHARLES B. FINK, OF EAST SYRACUSE, NEW YORK.

CAR-DOOR LOCK.

1,311,598.

Specification of Letters Patent. Patented July 29, 1919.

Application filed May 24, 1919. Serial No. 299,515.

To all whom it may concern:

Be it known that I, CHARLES B. FINK, a citizen of the United States of America, and resident of East Syracuse, in the county of 5 Onondaga, in the State of New York, have invented new and useful Improvements in Car-Door Locks, of which the following, taken in connection with the accompanying drawings, is a full, clear, and exact description.

This invention relates to certain improvements in car door locks as applied more particularly to the sliding doors of box cars having lower and upper guide rails for the cornering 10 responding edges of the door, although, it is equally applicable to any single or double sliding door or doors opening in one direction or the reverse.

One of the objects is to enable the same 20 device to be used on either of the upright edges of a sliding door to lock the same in its closed position both at the top and at the bottom, and at the same time to permit the locking members to be easily and quickly withdrawn by simple turning movement of 25 a rock arm to which the locking bars are connected.

Another object is to provide both locking 30 bars with offset portions extending across the rear edge of the door in close proximity to the guide rails and to provide said offset portions with locking bolts movable into and out of engagement with suitable bolt openings in the guides thereby constituting a 35 two-point bearing for each of the lower and upper edges of the door, one bearing being in the connection between the locking bolt and its corresponding guide rail, and the other bearing (the offset portion of the locking bar) close to the first-named bearing.

In other words, the main object briefly stated is to provide a door with a quick shift, a double lock which is interchangeable and reversible for either edge of the door and in 45 which the operating handle may be always placed in the most convenient position for manipulation of the locking bars from their closed to their opened positions with a movement of the handle through an arc of not to exceed 90°.

A further object is to provide the lower and upper corners of the rear edge of the door with metal brackets carrying suitable guides for the locking bolts so as to assure 55 proper entry of the bolts into their respective keepers in the lower and upper rails

without special attention on the part of the operator other than to see that the door is closed.

Other objects and uses relating to specific 60 parts of the device will be brought out in the following description.

In the drawings,

Figure 1 is a side elevation of a part of a box car body and door together with my 65 improved locking device, partly in section, in its locking position by full lines and in its unlocked position by dotted lines.

Figs. 2, 3 and 4 are detail sectional views taken respectively on lines 2—2, 3—3 and 70 4—4 Fig. 1.

In order that my invention will be clearly understood, I have shown a part of a car body —A— and a part of a slide door —B— capable of covering the usual opening in one 75 side of the body and adapted to be held in place against downward swinging movement by lower and upper guides —a— and —a'—, said guides being of the usual double flanged type and extending across the adjacent 80 edges of the door lengthwise of the car body having one flange secured to said body and its other flange overlapping the adjacent portion of the outer face of the door.

The locking device as shown comprises a 85 base plate —1— having a central outwardly projecting stud —2— upon which is centrally fulcrumed or pivoted a rock arm —3— having its opposite ends provided with 90 separate pairs of lugs —4—, those of each pair being arranged in spaced relation for receiving between them a hand lever —5— which is also pivotally mounted upon the stud —2— coaxial with the axis of movement of the rock arm —3—.

A pair of locking bars —6— are pivoted at one end at —7— to the rocking member —3— at opposite sides of the fulcrum or pivot —2—, the other ends of said locking bars being provided with angular offsets 100 —8— forming flanges —9— which extend transversely across the adjacent portions of the rear edge of the door —B—.

These flanges —9— are provided with extensions —10— constituting locking bolts 105 adapted to enter openings —11— in the adjacent guides —a— and —a'—.

The lower and upper corners of the rear edge of the door —B— are reinforced by triangular box-shaped brackets —13— of 110 suitable metal having integral lugs —14— provided with vertically aligned apertures

- 15— for receiving and guiding the adjacent portions of the locking bolts —10— into and out of their respective keeper openings —11— and assuring the proper entrance of said locking bolts into the openings when the door is closed and the locking bars moved to the locking position.
- 10 The base plate —1— is secured by bolts —16— or equivalent fastening means to the outer face of the door —B— near the rear edge thereof and substantially midway between the lower and upper edges of said door so as to cause the locking device, as a whole, with the exception of the keepers, to move with the door, and at the same time positioning said locking device at the rear edge of the door where the resistance to accidental opening of said door is most efficient.
- 15 20 The stud —2— projects outwardly from the base plate —1— a sufficient distance to receive the rocking member —3— and lever —5—, and its outer end is preferably threaded to receive a nut —2'— and one or more washers for holding the rocking member —3— and lever —5— in their operative positions, and at the same time permitting the lever —5— to be removed and reversed between the other pair of lugs —4—, if it should be desired to operate the locking device from the top of the car instead of from the bottom, or in case the locking device is placed upon the other upright edge of the door.
- 25 30 35 The rock arm —3— extends equal distances from opposite sides of its pivot —2—, beyond the edges of the plate —1—, the lugs —4— being preferably located at the extreme ends of the rock arm, and therefore equal distances from the pivot —2—.
- 40 The locking bars —6— are of substantially the same form and size except that their angular offsets —8— and locking bolts —10— are reversed, the object of this similarity being to permit the entire locking device to be placed upon either edge of the door according to the direction of opening but always upon the door near its rear edge.
- 45 50 55 The angular portions —8— are preferably longer vertically than the width of the shanks of the bars —6— and are preferably disposed in close proximity to the corresponding door guides —a— and —a'—, the purpose of elongating the angular offsets —8— being to afford relatively long bearings —9— for the adjacent portions of the rear edge of the door so as to better resist the accidental opening of said door when the latter is locked by the locking device.
- 60 65 70 The bolt guides —14— are positioned between the angular portions —8— and the adjacent guide rails —a— and —a'— and are of sufficient length to allow vertical movement of the locking bolts from one extreme position to the other without withdrawing

them therefrom which assures the reentrance of said bolts into their respective keeper openings —11— when shifted to their locking positions.

It is now evident that by providing the locking bars —6— with the stop shoulders or flanges —9— across the rear edge of the door close to the keepers —10— brings the resistance to the opening of the door close to the keepers so that the keepers and flanges may assist each other in firmly holding the door in its closed position when the bolts are locked.

The pivots —7— for the locking bars —6— are preferably placed between the lugs —4— of each pair and the pivot —2— but are spaced a sufficient distance from said pivot to withdraw the locking bolts from their keepers —11— or out of engagement with the guides —a— and —a'— when the locking member —3— is moved through an arc of not greater than 90° from its locking position.

The handle —5— extends from the pivot —2— between and beyond the lugs —4— of one pair and preferably downwardly where it is within convenient reaching distance from the ground to be turned a quarter turn for unlocking the bolts, when desired, said lever having a limited inward and outward movement by reason of a slight lost motion on the stud —2— to permit it to be moved into and out of engagement with a staple —17— which when the free end of the lever is pressed back toward the adjacent bar —6— enters a slot —18— in said bar and permits a sealing wire as —19— to be passed through the staple to seal the device in its locked position, each bar —6— being provided with one of the staples —17—.

In operation, assuming that the parts are in the position shown by full lines in Fig. 1, and that it is desired to open the door, the seal —19— may be broken, the lever —5— pulled out of engagement with the staple —17— and then turned either to the right or to the left as may be desired.

What I claim is:

1. A car door lock comprising lower and upper guide flanges for the door, said guide flanges having vertically aligned openings near the rear edge of the closed door, a plate secured to the door near its rear edge, a rock arm pivoted intermediate its ends upon the plate, and having each end provided with a pair of outwardly projecting lugs in spaced relation, locking bars pivoted at one end to opposite ends of said rock-arm and having their other ends offset across the rear edge of the door and provided with bolts movable into and out of said openings as the rock-arm is moved in reverse directions, and a hand lever pivoted coaxially with said rock-arm and normally disposed

between the lugs of one pair for turning the rock-arm, and thereby simultaneously moving both locking bars in reverse directions.

5. 2. In combination with a box car body and a sliding door therefor, a base plate secured to the outer face of the door near the rear edge thereof, a rock-arm pivoted to said plate and directly in opposite directions from its pivot, lock bars pivoted to said rock-arm at opposite sides of the first-named pivot and provided with flanges abutting against the rear edge of the door near the lower and upper edges thereof, said bars being provided with bolts for engaging keepers above and below the door.

3. In combination with a box car body and a sliding door therefor, keepers on the body near the rear edge of the door when the latter is closed, a rock-arm pivotally mounted on the door to swing in a plane parallel therewith, locking bars pivoted to the rock-arm at opposite sides of the first-named pivot and provided with abutments for engaging the rear edge of the door near the upper and lower edges thereof, said abutments being provided with extensions movable into and out of engagement with their respective keepers as the rock-arm is moved in reverse directions.

4. In combination with a box car body and a sliding door therefor, keepers on the body near the rear edge of the door when the latter is closed, a rock-arm pivotally

mounted on the door to swing in a plane 35 parallel therewith, locking bars pivoted to the rock-arm at opposite sides of the first-named pivot and provided with abutments for engaging the rear edge of the door near the upper and lower edges thereof, said 40 abutments being provided with extensions movable into and out of engagement with their respective keepers as the rock-arm is moved in reverse directions, and guides for said extensions secured to the adjacent portions of the door.

5. In combination with a box car body and a sliding door therefor, keepers on the body near the rear edge of the door when the latter is closed, a rock-arm pivotally 50 mounted on the door to swing in a plane parallel therewith, locking bars pivoted to the rock-arm at opposite sides of the first-named pivot and provided with abutments for engaging the rear edge of the door near 55 the upper and lower edges thereof, said abutments being provided with extensions movable into and out of engagement with their respective keepers as the rock-arm is moved in reverse directions, and means for 60 locking the rock-arm and locking bars against relative movement.

In witness whereof I have hereunto set my hand this 15th day of May, 1919.

CHARLES B. FINK.
